(57) **CLAIM**

The ornamental design for a fishing net, as shown and described.

DESCRIPTION

FIG. 1 is a front, right, and top perspective view of a fishing net, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a first part of a rod.

FIG. 9 is a partial enlarged view of an area labeled 9 in FIG. 1 comprising a second part of the rod; and,

FIG. 10 is a front, right, and top perspective view of the fishing net in FIG. 1, wherein the rod of the fishing net is shrunk.

The broken lines shown in the drawings are included for the purpose of illustrating portions of the fishing net that form no part of the claimed design.
